MODEL RACING CAR

Derek Gardner, West Horsley, England, assignor to Tyrrell Racing Organisation Limited, Long Reach, Ockham, England

Filed June 28, 1971, Ser. No. 157,782

Claims priority, application Great Britain Dec. 29, 1970

Term of patent 7 years

Int. Cl. D21—01

U.S. Cl. D34—15

FIG. 1 is a left side elevational view of a model racing car showing my new design, the right side being a mirror image thereof;

FIG. 2 is a front elevational view thereof;

FIG. 3 is a top plan view thereof; and

FIG. 4 is a rear elevational view thereof.

I claim:

The ornamental design for a model racing car, as shown and described.
